CLAIM

The ornamental design for a lens insert for frames, as shown and described.

DESCRIPTION

FIG. 1 is a front isometric view of the lens insert for frames of the present invention;
FIG. 2 is another front isometric view thereof;
FIG. 3 is a rear isometric view thereof;
FIG. 4 is another rear isometric view thereof;
FIG. 5 is yet another front isometric view thereof;

(Continued)

FIG. 6 is a front view thereof;
FIG. 7 is a rear view thereof;
FIG. 8 is a top plan view thereof;
FIG. 9 is a bottom plan view thereof;
FIG. 10 is a left-side view thereof; and,
FIG. 11 is a right-side view thereof.

1 Claim, 11 Drawing Sheets
